UNITED STATES PATENT OFFICE.

CHRISTOPHER F. BACKMYER, OF CHICAGO, ILLINOIS.

GARMENT-FASTENER.

1,216,262.

Specification of Letters Patent. Patented Feb. 20, 1917.

Application filed October 15, 1915. Serial No. 55,991.

To all whom it may concern:

Be it known that I, CHRISTOPHER F. BACKMYER, a citizen of the United States, and a resident of the city of Chicago, in the county of Cook and State of Illinois, have invented a certain new and useful Improvement in Garment-Fasteners, this said invention being in part a continuation of my application for Letters Patent filed in the United States Patent Office on February 26, 1915, Serial No. 10,715; and I do hereby declare that the following description of my said invention, taken in connection with the accompanying sheet of drawing, forms a full, clear, and exact specification, which will enable others skilled in the art to which it appertains to make and use the same.

My invention relates generally to improvements in garment fasteners, and it consists, essentially, in the novel and peculiar combination of parts and details of construction, as hereinafter first fully set forth and described and then pointed out in the claims.

In the drawing to which reference has already been made, the figures or views of my device are enlarged to many times life size in order to more clearly disclose the details of construction of the preferred and modified structures constituting the invention. In these views, Figure 1 is a plan of a blank of thin sheet metallic material employed in the production of the eye-member of my invention. Fig. 2 is a combined cross section of an eye member and a stud member in their completed or finished form as being introduced to each other. Fig. 3 is a like cross section of the said stud and eye members as partially connected together, and Fig. 4 is a similar section showing the said parts in completely connected position, as hereinafter more fully set forth. Fig. 5 is a horizontal section in plan, in line 5—5 of Fig. 2. Fig. 6 is a like section in line 6—6 of Fig. 3, and Fig. 7 is a similar section in line 7—7 of Fig. 4. Fig. 8 is an axial, vertical section of the eye member, illustrating a slight modification of the structure therein, and Fig. 9 is a bottom plan thereof. Fig. 10 is a cross section of the stud member as employed in Figs. 2, 3, 4, 5, 6 and 7, and Fig. 11 a bottom plan of the same. Fig. 12 is a vertical cross section of the stud member employed in connection with Figs. 8 and 9,

which structure is considered a clear equivalent of Fig. 10. Fig. 13 is a bottom plan of Fig. 12.

Like parts are indicated by corresponding characters or symbols of reference in all the figures of the drawing.

The aim of this invention is the production of a fastener for the overlapping edges or seams of dresses, coats, waists and other garments in which the disadvantages of the typical hook and eyes are eliminated. Among these disadvantages may be named the liability of the hooks and eyes becoming disengaged from each other whereby the flap or seam of the garment becomes loosened and presents an unsightly appearance.

Another result aimed at in my invention resides in the details of construction whereby the difficulty of hooking together the typical hooks and eyes is eliminated, and wherein a pull upon the fabric to enforce engagement of the parts is avoided. And yet another advantage aimed at in this invention is to so construct the elements thereof that when the waist or other garment to which this fastener is attached is being ironed or passed through a wash ringer, there will be no tendency to distort the fastener itself and destroy its usefulness, as is now the case with the usual type of hooks and eyes.

In the construction of my invention the eye member thereof, shown in flat form in Fig. 1, is produced from a thin sheet metallic blank A of essentially disk like form a, having a long protruding member B, projecting radially from the margin of said disk a, and a shorter projection b, extending from the periphery of said disk a at a point opposite that of the projection B. Piercing the substantial center of the disk like portion a is a substantially circular opening a', from which extends a slot a'', as clearly seen in Fig. 1.

Arranged concentrically about the disk a are a series of apertures a''', which apertures may be circular or elongated as desired and are adapted to form openings through which thread may be passed whereby the eye member may be sewn to a piece of fabric such as that composing a woman's waist or dress.

The blank A, constituted as aforesaid, is

adapted to have its disk like portion *a* to be pressed or stamped into the shape of a dome, with the projecting portion *B* bent back and under the said dome and the shorter projection *b* also bent back and under the dome in such a manner that the free end of the portion *B* may rest upon the projection or lip *b* as seen, for instance, in Figs. 2 or 8. The material from which the blank *A* is produced is preferably of a springy nature, such as spring sheet brass, steel, or German silver, and the portion *B* already referred to is provided with a depression *C* below the openings *a'* and *a''* in the dome *a*. This depression may be in the form of a V-shaped groove struck transversely of the member *B* as seen at *C'*, dotted lines, Fig. 1, or in the conformation of a sunk groove as in Fig. 8. In either case, the essentials of the groove or depression are the same; *i. e.*, that the walls thereof form upwardly inclined walls 10 and 11 extending in opposite directions longitudinally of the member *B*.

The stud member of my device which may 25 be termed *E* as a whole, is made from thin sheet metal in disk like form and possessed of a curled or like stiffening edge *E'* and thread fastening openings *E''* or the like. This stud member is provided with an up- 30 standing stud *F*, having an enlarged head *G*, and the outer outline of this head is made to fit the depression *C* in the spring member *B*, whether the said depression be V-shaped or arcuate as the case may be.

35 In connecting together the eye member and the stud member of my invention, it is simply necessary to enter the head *G* of the stud member through the eye *a'* of the eye member. Upon downward pressure being 40 applied upon the stud member one side of the stud head *G* thereof will engage the side 10 of the depression *C* in the member *B*. Free downward movement of the latter member *B* being estopped by the lip or pro- 45 jection *b*, a deflection of the said member *B* is caused to take place upon the application of further pressure upon the stud member *B* until the head *G* is totally lodged in the depression *C*, during which process the stud 50 member itself with its head has been laterally moved so that the stud *F* is in engagement with the cut out portion *a''* of the opening *a'*, whereby an upward retraction of the head *G* is prevented, unless the 55 same be forcibly moved to register with the opening *a'* in an evident manner.

I have hereinbefore disclosed the preferred mode of practising my invention, but I reserve the right to make such and any 60 changes as might occur to one skilled in the art to which this invention appertains, or to make any and all such alterations as may be permitted under the doctrine of equivalents.

Having thus fully described my invention I claim as new, and desire to secure to myself by Letters Patent of the United States:—

1. In a garment fastener, an eye member thereof comprising a single sheet metallic 70 blank and a projecting tongue extending therefrom, there being a shorter tongue extending from the opposite side of said blank, both of said tongues being bent back under said blank with the said shorter tongue preventing downward movement of said first 75 named tongue, there being an opening through said blank above said first named tongue.

2. In a garment fastener, an eye member 80 therefor comprising a single sheet metallic blank having an opening therethrough and a tongue extending from one margin of said blank, a shorter tongue extending from the opposite margin of said blank, both of said 85 tongues being bent back under said blank, with said shorter tongue supporting the free end of said first named tongue, said first named tongue having a depression in the upper face thereof beneath said opening 90 in said blank.

3. In a garment fastener, an eye member therefor comprising a single sheet metallic blank having an opening therethrough and a tongue extending from one margin of said 95 blank, a shorter tongue extending from the opposite margin of said blank, both of said tongues being bent back under said blank, with said shorter tongue supporting the free end of said first named tongue, said 100 first named tongue having a depression in the upper face thereof beneath said opening in said blank.

4. In a garment fastener, an eye member therefor comprising a single sheet metallic 105 blank possessed of oppositely extending tongues bent back under said blank, with one of said tongues adapted to support the other of said tongues, there being an opening through said blank.

5. In a garment fastener, an eye member therefor comprising a single sheet metallic blank possessed of oppositely extending tongues bent back under said blank toward each other, with one of said tongues adapt- 115 ed to support the other of said tongues, there being an opening through said blank, and in one of said tongues a transverse, conical, depression, said depression being underneath the opening in the blank.

6. A garment fastener including a hollow dome shaped member possessing an integrally formed spring leaf bent back and contained within said dome, said dome having a circular opening from which extends 125 a slot, the said spring leaf having a V-shaped depression located below a portion of said opening and said slot, and a stud

member having an enlarged conical head and a reduced neck, said head being adapted for entrance through said opening and engagement with one of the inclined sides 5 of said V-shaped depression, whereby upon the application of pressure upon said stud member, the engagement of said head with

said inclined side will enforce horizontal movement of said stud member and the entrance of said reduced neck into said slot. 10

In testimony that I claim the foregoing as my invention, I have hereunto set my hand.

CHRISTOPHER F. BACKMYER.
